UNITED STATES PATENT OFFICE.

DAVID JOSEPH CONDON, OF GOODLAND, INDIANA.

CANOPY FOR DRAFT-ANIMALS.

No. 923,021.

Specification of Letters Patent.

Patented May 25, 1909.

Application filed August 19, 1908. Serial No. 449,340.

To all whom it may concern:

Be it known that I, DAVID JOSEPH CONDON, a citizen of the United States, residing at Goodland, in the county of Newton and 5 State of Indiana, have invented a new and useful Canopy for Draft-Animals, of which the following is a specification.

A canopy for draft animals should be inexpensive in construction, facile in operation 10 and devoid of complicated parts; it should be capable of manipulation at the driver's hands without necessitating his leaving the seat, or at most it should not require his descent from the vehicle; it should combine 15 in a single operative device, maximum protection with maximum rigidity and durability, its care and operation demanding minimum effort; and these ends are sought to be effected by my invention.

20 With these and other objects in view, as will hereinafter more fully appear, the invention consists in the novel construction and arrangement of parts hereinafter described, delineated in the accompanying 25 drawing and particularly pointed out in the appended claims, it being understood that various changes in the form, proportions, size and minor details of the structure may be made without departing from the spirit 30 of the invention or sacrificing any of its benefits.

Similar numerals of reference are employed to denote corresponding parts throughout the several figures of the drawings.

In the accompanying drawings:—Figure 1 shows my invention, in perspective, mounted upon the front of a vehicle; Fig. 2 is a side elevation thereof, parts being broken 40 away; Fig. 3 is a side elevation, showing, in detail, the toggle levers, their locked position being shown in solid line, and their unlocked position in dotted line; Fig. 4 is a detail perspective, showing the means 45 whereby the lazy-tongs is slidably mounted upon the supporting member.

In carrying out my invention, I provide a frame depending upon the lever principle as embodied in the form commonly known 50 as the lazy-tongs. This frame in its preferred form, consists of the vertically disposed, horizontally extensible lazy-tongs 8, for lightness made to taper toward their movable end, as shown in Fig. 2. The lazy- 55 tongs 8 carry the tie-rods 3, upon which are mounted the slats 32, trussed into an up-

wardly convexing curve by the tie-rods 3. The slats 32 may be of greater length than the tie-rods 3 and the canopy cloth 2 which is carried by the slats 32 thereby extended 60 beyond the lazy-tongs 8 to any desired degree, the upwardly convexed curve assumed by the tie-rods 32 serving so to dispose the canopy-cloth 2 as to form a water-shed. I further provide a standard 4 adapted to 65 carry one end of the lazy-tongs 8. The standard 4 has its lower end attached to the front of a vehicle and may, if desired, be braced or otherwise secured in position. The standard 4 may be variously formed; in 70 practice, I prefer to provide a tubular socket 5 within which is rotatably mounted a rod 6, a set screw 19 and a collar 1 slidably mounted upon the rod 6, furnishing means for adjusting vertically the rod 6 in the socket 5. 75 A frame 7 preferably rectangular, is carried by the rod 6 and may be formed integral therewith.

The terminal upper connections 9 between members of the lazy-tongs are rigidly attached to the uprights 10 of the rectangular frame 7 and the corresponding, terminal lower connections 11 between members of the lazy-tongs, are slidably carried by the uprights 10, the terminal upper members 12 85 being prolonged to form the operating levers 20.

The sliding connection between the terminal lower connections 11 and the uprights 10 may be variously effected; I prefer, however, to attach to the inner sides of the uprights 10, the guides 21, through which may be passed, the terminal lower member 22 of the lazy-tongs 8. The members 23 which unite with the terminal lower members 22 95 to form the terminal lower connections 11, may have their lower ends prolonged and bent outward to form feet 24, fulcrumed against the uprights 10 under the weight of the lazy-tongs 8 and their superposed members.

Pivots mounted upon the vehicle tongue 25 is the strut 15 adapted to support the movable end of the lazy-tongs 8 when the said lazy-tongs are extended. The strut 105 15 may comprise the tube 17, hinged to the tongue 25 by any simple means, such as the one shown 26. Mounted in the tube and slidably adjustable therein, is the canopy support 18, each of its bifurcations 27 pivotally connected to one of the lazy-tongs 8, as shown at 28.

Slidably mounted upon the canopy support 18 is the collar 29, retained by the set screw 30. Attached to the lower end of the collar 29 is the spring 31, contacting with 5 the top of the tube 17 and bearing yielding the canopy support 18.

The toggle levers 13 are shown in detail in Fig. 3. These members have their rear ends attached to the uprights 10, as shown 10 at 14, their forward ends being pivoted to the lazy-tongs 8, as shown at 33. The levers are pivotally united, as shown at 34, and when the lazy-tongs is extended the toggle levers may be forced down into locking position, shown in solid line in Fig. 3, 15 maintaining the lazy-tongs frame in an extended position. The toggle-levers may be up-struck from their locked position to the unlocked position, shown in dotted line in Fig. 20 3, whereupon the lazy-tongs may be retracted toward the supporting members and into the position indicated in dotted line in Fig. 3.

In operation, when, as shown in the accompanying drawing, the canopy is extended, the toggle-levers 13 are forced upward into an unlocked position, manual pressure is applied to the levers 20, the terminal lower members 22 moved downward 30 within the guides 21 and the lazy-tongs 8 closed together, bringing the canopy cloth 2 together in a compact mass near the front of the vehicle. The tube 17 will hinge toward the wagon upon the union 26 and 35 the canopy support 18, being pivotally connected at 28 with the lazy-tongs 8, will be carried rearward toward the wagon, the slidable connection between the canopy support 18 and the tube 17 permitting the former to be drawn out from the latter.

When it is desired to extend the canopy over the draft animals, the lever 20 is manipulated forcing the lower terminal member 22 upward within the guards 21, extending 45 the lazy-tongs 8. The canopy support 18 will be moved forward by the lazy-tongs 8 and telescoped into the tube 17 which will assume an upright position, the spring 31 yieldingly upholding the canopy support 18. 50 The toggle-levers 13 are then shoved downwardly into the locked position shown in the drawing, holding the canopy extended.

The rod 6 being rotatable in the socket 5, the lazy-tongs 8 will follow the lateral move-

ments of the tongue 25, the spring 31 absorbing the vertical movements of the tongue. 55

Having thus described my invention, my claims are as follows:—

1. In a device of the class described, a horizontally extensible lazy-tongs frame; means for attaching one end of the lazy-tongs frame to the front of a vehicle; a tube arranged to be hinged to the tongue of a vehicle; a canopy-support pivotally connected with the lazy-tongs frame, and having its lower terminal mounted in the tube and slidably adjustable therein. 65

2. In a device of the class described, a horizontally extensible lazy-tongs frame; 70 means for attaching one end of the lazy-tongs frame to the front of a vehicle; a tube arranged to be hinged to the tongue of a vehicle; a canopy-support pivotally connected with the lazy-tongs frame, and having its lower terminal mounted in the tube and yieldingly supported therein. 75

3. In a device of the class described, a rectangular frame; a pair of vertically disposed, horizontally extensible lazy-tongs 80 carried by the uprights of the rectangular frame; toggle levers terminally connected with the uprights of the rectangular frame and the lazy-tongs.

4. In a device of the class described, a rectangular frame; a vertically disposed, horizontally adjustable lazy-tongs mechanism having its terminal, upper connection between two of its members rigidly attached to one of the uprights of the rectangular frame, the corresponding terminal, lower connection, being slidably mounted upon the upright, the forward element of said lower connection being terminally bent to form a frame-engaging foot; a guide 95 mounted upon the upright and being arranged to inclose the rearward element of the terminal, lower connection; and the terminal, upper member of the lazy-tongs being prolonged to form an operating lever. 100

In testimony that I claim the foregoing as my own, I have hereto affixed my signature in the presence of two witnesses.

DAVID JOSEPH CONDON.
